DESIGN FOR A LEG FOR A PEDESTAL BASE

Samuel D. Loman, Chicago, Ill., assignor to Products Development, Inc., Chicago, Ill., a corporation of Illinois

Application April 2, 1945, Serial No. 118,822

Term of patent 14 years

(CL. D15—8)

To all whom it may concern:

Be it known that I, Samuel D. Loman, a citizen of the United States, residing at Chicago, in the county of Cook and State of Illinois, have invented a new, original, and ornamental Design for a Leg for a Pedestal Base, of which the following is a specification, reference being had to the accompanying drawing, forming part thereof.

Figure 1 is a side elevational view of a leg for a pedestal base, showing my new design.

Fig. 2 is an end elevational view of the leg looking toward the right in Fig. 1.

Fig. 3 is an enlarged horizontal sectional view taken in the plane of line 3—3 of Fig. 1.

Fig. 4 is an enlarged vertical sectional view taken on the line 4—4 of Fig. 1.

Fig. 5 is a top plan view of the leg as seen when rotated 180° from the position of Fig. 1.

I claim:

The ornamental design for a leg for a pedestal base, substantially as shown.

SAMUEL D. LOMAN.
